COMPARATOR GAUGE

Filed July 24, 1967

INVENTOR
ARTHUR E. CLARK

BY
Frank Knott & Gifford
ATTORNEYS.

In practice, the gauge head is set quickly by loosening the thumbscrew 16 and moving the head to a position where the twist drill 58 can be held against edge 50 of slide 14 and the thumbscrew tightened as shown in FIG. 4. As some drills are provided with shanks 54 of greater diameter than their bodies such as square or tapered shank drills, for example, and indicated by the dashed lines 60, applicant's gauge allows the full body of the drill to be aligned in contact with edge 50 of the slide. It will be noted that blade 20 has its edge 62 sloped at an angle of 59° for checking the point 56 of the drill 58. The 59° angle is, of course, standard for most drill applications and allows for quick comparison to see if the drill has been correctly ground. The other edges of the blade 20 are sloped at other angles for checking the angles of other types of drills or cutting tools.

The head 12 can be positioned at either end of the slot 28 to provide a sufficient side edge on the slide 14 against which the shank of the tool will lie. Scales 63 are preferably inscribed along both sides of the slide 14 for checking tool lengths. Scale 65 inscribed on the edges of the blades 18 and 20 are used to check the dimensions of the two drill cutting edges to insure uniformity and accuracy.

An alternative form of base scale is shown in FIG. 5 wherein the base 64 is provided with a series of threaded holes 66 to allow the head 12 to be positioned at various fixed locations along the base.

Although I have described the preferred embodiments of my invention, it will be understood that many modifications and revisions may be made therein without departing from the spirit of the invention.

What is claimed is:

1. A gauge, comprising:

- (a) a head having a pair of spaced, opposed sides, 35 and a straight marginal edge meeting at least one of the opposed sides;
- (b) an elongated slide having a straight, longitudinal side edge and a longitudinal slot parallel to said straight side edge, the slide being receivable between 40 the opposed sides of the head in a position in which the straight side edge is adjacent the straight marginal edge; and
- (c) means for fastening the head and the slide together including means for laterally spreading the longitudinal sides of the slide into engagement with the opposed sides of the head whereby the straight side edge of the slide and the straight marginal edge of the head meet one another to form a reference angle for comparison with the angular profile of a tool. 45

2. The combination as defined in claim 1, in which the last mentioned means comprises a retainer releasably engagable with the slide to allow the head to be fastened at a selected longitudinal position along the slide.

3. The combination as defined in claim 1, including 55 indicia inscribed on the head along its straight marginal edge.

4. The combination as defined in claim 1, in which

said last mentioned means comprises a leaf spring retainer for biasing opposite sides of the slot away from one another.

5. A combination as defined in claim 1, in which said last mentioned means comprises a wedge retainer for spreading opposite sides of the slot away from one another.

6. The combination as defined in claim 1, in which the head has a second straight marginal edge meeting one of said opposed sides, and the slide has a straight longitudinal edge for meeting the second straight marginal edge to form a second reference angle.

7. The combination as defined in claim 6, in which the two straight marginal edges of the head meet opposite one of the opposed sides.

8. The combination as defined in claim 6, in which the two straight marginal edges of the head meet the same opposed side.

9. A gauge having a reference angle for comparison with the contour of a twist drill point, comprising:

- (a) a head having a pair of planar blades fixed with respect to one another, each blade having a straight edge opposing and parallel to a similar straight edge of the other blade, at least one straight marginal edge meeting said blade straight edge in a predetermined angle to form a corner, and indicia formed along said straight marginal edge;
- (b) an elongated slide having a longitudinal slot formed between a pair of straight longitudinal sides, the slide being received between the opposing blade straight edges in a position in which each straight longitudinal side is adjacent a corner of the head; and
- (c) a fastener connecting the head and the slide to releasably lock them together, and means on said fastener spreading the straight longitudinal sides of the slide into contact with the opposing blade straight edges such that each straight longitudinal side meets a straight marginal edge to form a predetermined reference angle at their juncture for comparison with the angle between the cutting edge and the shank of a twist drill.
